UNITED STATES PATENT OFFICE.

JACOB B. BLAW, OF ATLANTIC CITY, NEW JERSEY.

ADJUSTABLE FIRE-HOSE-NOZZLE SUPPORT.

Application filed November 18, 1920. Serial No. 424,844.

To all whom it may concern:

Be it known that I, JACOB B. BLAW, a citizen of the United States, and resident of Atlantic City, county of Atlantic, and 5 State of New Jersey, have invented an Improvement in Adjustable Fire-Hose-Nozzle Supports, of which the following is a specification.

The object of my invention is to provide 10 a portable fire hose play-pipe or nozzle support which may be quickly clamped in position upon a window sill or any available part of a building and act as an adjustable support for the hose play-pipe or nozzle 15 while it is throwing a stream of water, the construction being such as to remove objectionable strain from the firemen in handling the hose line and play-pipe and whereby one fireman may handle the play-pipe or 20 nozzle unassisted.

My object is also to so construct the play-pipe or nozzle supporting means that it is not only capable of adjustment in its attachment to the building, but is also adapted 25 for adjustment to provide an immediate support for the play-pipe or nozzle, whereby the latter may have capacity for universal adjustment so as to throw the stream in whichever direction may be required.

With the above and other objects in view, the nature of which will be more fully understood from the description hereinafter, the invention consists in the novel construction of adjustable fire hose play-pipe or 35 nozzle support, as hereinafter more fully described and defined in the claims.

Referring to the drawings: Fig. 1 is a sectional elevation of a fire hose nozzle support, taken on line 1—1 of Fig. 2; Fig. 2 40 is a rear elevation of the same; Fig. 3 is a transverse section taken on line 3—3 of Fig. 1; Figs. 4 and 5 are diagrams illustrating the adjustable capacity of the frame structure and Fig. 6 is an elevation of the adjustable play-pipe or nozzle clamp forming part of my invention.

In general, the frame constituting the adjustable support comprises a front frame 2 and a rear frame 3 and a connecting frame 4 at the top which is of relatively small size to which is hinged the upper ends of the front and rear frames 2 and 3 by means of transverse hinge bolts 5. The frames 2 and 3 are preferably of malleable castings 55 and are more or less of triangular shape and with the upper ends extended to form

slightly flexible arms 6 constituting the hinge connections with the top frame 4, said arms adapted to be clamped to the said top frame by the bolts so as to apply to the 60 hinged joint so formed any desired degree of friction. The object of this frictional jointed connection between the front and rear frames is to retain any angular adjustment of the top frame which may be 65 required when directing the nozzle supported thereon by the means now to be described.

The top frame 4 acts as a support for a ring shaped clamp 7 through which the nozzle is extended and held, the said clamp 70 provided at its bottom with a vertical pin 8 loosely extending through the frame 4, and held thereon by means of a nut 9 on its lower end and preferably with a spring washer 10 interposed between the nut and 75 the bottom of the frame 4, so that the ring shaped holder of the nozzle will tend to hold itself in any position of adjustment. The ring shaped clamp constituting the immediate holder for the nozzle is preferably 80 formed of a U shaped socket portion 11 to which is hinged an inverted U shaped top portion 12, the two parts being jointed to one side at 13 and having the opposite ends provided with holes 14 adapted to come into 85 alinement when the two parts are closed into ring shaped adjustment and in which closed position of adjustment they may be retained by a pin 15 which may be thrust through 90 the alined holes. To prevent the pin being lost, it may be connected by a short chain 16 with the nozzle holder. Clamp 7 may be pivoted on a universal joint as in Fig. 6.

More specifically referring to this construction, 11^a constitutes a yoke having a 95 vertical pivot pin 8 by which it is pivoted to frame 4, and to the upper ends of the yoke there is pivoted at 11^b, on a transverse axis, the ring-shaped clamp 7 for the play-pipe or nozzle, said clamp comprising the 100 U shaped socket part 11 to which is hinged at 13 the top portion 12. This top clamping portion 12 may be closed down on the socket part 11 and secured thereto by bolt 15 passing through alining holes 14 in the parts 105 11 and 12. By use of this construction, the clamp 7 and the play-pipe or nozzle carried thereby may be adjusted about the pivots 11^b and the axis of the bolt 8, as may be required, the device having capacity for 110 universal adjustment. The clamping device may be made in any other suitable manner

for detachably supporting and clamping the play-pipe or nozzle.

The lower and spreading portions of the frames 2 and 3 are provided with claws 5 which may take hold upon the window sill or other portion of the building to which the device is to be clamped, and these claws may be integrally fixed to the lower-ends of the frames or adjusted thereto, as shown 10 in connection with the rear frame 3. In this case, the claws are formed on the bottoms of rods 18 which are adjustable longitudinally in sockets 19 in the lower ends of the frame 3, and in adjusted position in 15 which they may be clamped by set screws 20. By extending the rods, a greater capacity is given to the device as a whole for clamping upon wider or narrower sills or other objects to which the device is required 20 to be clamped. If desired, the adjustability of the claws may be dispensed with and the claws formed fixedly upon the lower ends of the frames themselves. As shown, each 25 of the frames 2 and 3 are provided with sockets 21 in which trunnions 22 of blocks 23 are journaled, and said trunnions are held in place by light straps 24 extending over the trunnions and riveted in place upon the frames. In this manner the blocks are 30 free to adjust themselves on the transverse axes provided by the trunnions. Extending through the blocks 23 on the rear frame 3 is an adjusting screw threaded rod 25 which is shouldered on the outer side to fit against 35 the block and is provided on the inner side with a collar 26 pinned in place so that the screw threaded rod is not permitted to shift longitudinally in respect to this block. The other or free end of the screw threaded rod 40 extends through a screw threaded hole in the other block 23 on the front frame, and moreover the rear end of the screw threaded rod may be provided with a handle 28 in crank or other form by which it may be 45 readily rotated when adjusting the two frames 2 and 3 toward or from each other. It will now be understood that when the two frames 2 and 3 are spread so that the claws thereof may be placed in proper position 50 upon the window sill and the screw threaded rod rotated, said frames 2 and 3 will be drawn toward each other until the claws tightly grip upon the sill. When this takes place, the fire hose nozzle may be 55 placed in position in the ring shaped clamp 7 and supported thereby without the necessity of relying upon the firemen to hold it. Thereafter, the hose may be adjusted 60 in a vertical plane to throw the stream obliquely upward or downward or horizontally, as the case may be, by merely applying pressure to the hose in which case the top frame 4 will be oscillated and the front and back frames 2 and 3 will adjust themselves 65 automatically to permit such adjustment.

ment of the top frame, said front and back frames rocking slightly upon the claws where they are attached to the sill. In addition to this adjustment in a vertical plane, the nozzle may be also given an adjustment 70 in a horizontal or any oblique plane, according to the adjustment of the frame 4, this being permitted by the oscillation of the ring clamp about its axial connection with the top frame 4.

From the foregoing, it will be seen that the hose play-pipe or nozzle is supported in such manner that it may be freely adjusted in vertical or horizontal planes at will, without any further adjustment in connection 80 with the sill or its other means of support. The ring shaped clamp for the hose play-pipe or nozzle may be held against axial oscillation by means of a clamping screw 27 carried by the top frame 4 at its side 85 and which may be radially manipulated when desired. It is also evident that any degree of friction may be put upon the jointed connection of the parts 2, 3, 4 and 7 by simply tightening the nuts upon the 90 plates and the vertical stem of the ring shaped hose clamp, whereby under any reasonable handling of the hose, the same will retain its adjusted position. It will, therefore, be only under special conditions that the clamping means 27 will be necessary.

In practice, this adjustable supporting means for the play-pipe or nozzle, while intended largely for adjustment to the window sill whether the hose play-pipe or nozzle is to be operated from the inside of the building outward to direct the stream to burning buildings or other portions of the same building, or whether it is to be operated from the outside of the building for projecting a stream into the building, nevertheless, the adjustability of the clamping means is such that it may be clamped, if necessary, upon overhead rafters or joists or to vertical posts or to a plank which itself may be nailed to the floor of a place. Moreover, the whole construction is light and portable and easily transported for use wherever necessary. I have shown the apparatus as made largely of malleable castings and while I prefer this manner of making the parts, I do not confine myself thereto.

It will now be apparent that I have devised a novel and useful construction which 120 embodies the features of advantage enumerated as desirable, and while I have in the present instance shown and described the preferred embodiment thereof which has been found in practice to give satisfactory 125 and reliable results, it is to be understood that I do not restrict myself to the details, as the same are susceptible of modification in various particulars without departing from the spirit or scope of the invention.

Having now described my invention, what I claim as new and desire to secure by Letters Patent, is:—

1. In a portable fire hose nozzle supporting means, the combination of a jointed frame structure in which the several parts are normally jointed in frictional contact sufficient to retain the parts in various positions of adjustment and having clamping jaws at its lower part, adjusting devices for drawing the jaws toward each other for gripping a window sill or other object, and a nozzle clamp comprising two curved parts hinged together to form a ring and provided with engaging means to hold the two parts in rigid relation, said nozzle clamp adjustably carried on the upper part of the frame structure.
2. In a portable fire hose nozzle supporting means, the combination of two frames having clamping jaws at the bottom and respectively hinged together at the top and provided thereat with a nozzle clamp, means for adjusting the two frames toward each other for clamping them to a window sill or other object, said means consisting of two upright adjustable blocks respectively pivoted to the hinged frames on transverse axes, a substantially horizontal rotatable screw forming a connection between the two hinged frames and having a hand operable

part for rotating it relatively to the adjustable blocks.

3. The invention according to claim 2, further characterized by having a top frame 35 frictionally hinged to each of the hinged frames, said top frame directly supporting the nozzle clamp and by means of which the nozzle clamp is permitted to have an oscillatory adjustment in a vertical plane. 40

4. The invention according to claim 3, wherein the upper parts of each of the two adjustable frames are provided with flexible hinged arms which are frictionally clamped to the top oscillatory frame by means of 45 transverse bolts which while acting as hinged journals for the several parts also provide means for adjusting the friction, whereby the hinged frames and top oscillatory frame may be given adjustments in 50 a vertical plane without removing the device from its clamped position upon the window sill or other object when it is desired to adjust the nozzle in a vertical plane.

5. The invention according to claim 2, 55 further provided with extensible claws constituting the clamping jaws upon one of the hinged frames, whereby its length may be increased.

In testimony of which invention, I here- 60 unto set my hand.

JACOB B. BLAW.
